UNITED STATES PATENT OFFICE.

FRANZ PUENING, OF PITTSBURGH, PENNSYLVANIA.

ART OF AND APPARATUS FOR DISTILLING CARBONACEOUS MATERIALS.

Application filed February 11, 1922. Serial No. 535,791.

This invention relates to the art of distilling carbonaceous material, such as lignite, shale, peat or bituminous coal. An object of the invention is to effect the distillation of such material at low temperatures, with a rapid transfer of the distilling heat to the material being distilled, and without any necessity for employing the expensive heating surfaces heretofore required because of the slow and inefficient heat transfer of prior low temperature distillation practice. The invention, therefore, provides an entirely satisfactory low temperature distillation, and yet eliminates expensive retort constructions, with their attendant high cost of maintenance.

In addition to the general objects recited above, the invention has for further objects such other improvements and advantages in operation and results as may be found to obtain in the processes or apparatus hereinafter described or claimed.

In the accompanying drawing forming a part of this specification and showing, for purposes of exemplification, one form of apparatus for carrying out the improved low temperature distillation of the present invention, but without limiting the claimed invention specifically to such illustrative instance:

Figure 1 is a sectional elevation of apparatus suitable for practicing low temperature distillation of materials according to the present invention;

Figure 2 is an enlarged sectional view of the retort or distilling chamber;

Figure 3 is an enlarged view partly in section of the ram for pushing out the distilled material; and

Figure 4 is a transverse sectional view taken through the distilling chamber.

In its present embodiment, the invention is applied to the low temperature distillation of bituminous coal, for producing coherent coke, such as is available for domestic heating purposes. For convenience, the ensuing description will be confined to this application of the invention. The novel features and improvements of the invention are, however, applicable to the distillation of other carbonaceous material, for example, to any of the other materials hereinabove mentioned; hence, the scope of the invention is not confined to the specific use and specific embodiment herein described as an illustrative example.

In carrying out the invention, there are employed, as the medium for effecting the transfer of the distilling heat to the material to be distilled, heating walls of a substance of high enough heat conductivity to effect a rapid transfer of the distilling heat to the material, for example, bituminous coal. It is preferable, however, to employ metal heating walls, iron, in any one of its several forms, being especially suitable because of its great specific weight, its high heat conductivity, its good wearing qualities, its resistance to deterioration when subjected to rapid temperature changes and the influence of hot gases, and lastly, because of its cheapness. The invention, however, is not limited to the employment of iron as the material for the heating walls.

These heating walls are first exposed to the action of hot gases to store in them the heat which is subsequently employed for effecting the distillation of the material. Any hot gases may be employed, provided that they are not of such a nature as to readily injure the heating walls. In any case, the temperature to which the heating walls may be heated is limited by the resistance or tendency of the material of which they are composed of oxidize or be otherwise impaired at high temperatures. In case iron is employed, however, the walls may be heated to a temperature of about 1400° F. in an atmosphere of well burned gases, without unduly exposing the iron to deterioration.

With iron heating walls heated to a surface temperature of 1400° F., distillation of the coal may be effected by bringing the coal into direct contact with such previously heated walls. The coal to be distilled may be either at ordinary atmospheric temperature, prior to the time of contact with the heating walls, or may be preheated, if desired. At the moment of contact, coal quickly absorbs the peak of the heat stored in the surface of the walls and in the portions of such walls just below its surface. The particles of the coal in contact with the heating walls are thus rapidly heated, the heat penetrating into the interior of the coal. During the heating up stage, a dry skin of coke is formed on the coal, thereby permitting ready separation of the coal from the walls at the completion of the distillation operation. As the heat transfer from the walls to the coal progresses, the flow of heat into the coal diminishes in rate,

along with the approach of the coal and the heating walls into an equilibrium of temperature. In order to avoid an impractical slowing up of the heat transfer, after the 5 initial rapid heat absorption by the coal, the weight of the heating walls, with respect to the coal being distilled, is regulated so that the storage capacity for heat of the walls is in excess of the heat required to bring the coal 10 to the required final temperature. The final temperature varies, of course, with different coals and with the other materials available for treatment by the distillation process of the invention. For many of such materials, 15 however, a satisfactory final temperature is approximately a thousand degrees F. and the process of low temperature distillation would be completed at that temperature. It requires about 400 B. t. u. per pound of material, 20 in order to heat commercial grades of bituminous coal to a final temperature of a thousand degrees F. In order to attain such a final temperature, a maximum temperature drop of the heating walls from 1400° F. to a 25 thousand degrees F. is available. Between 1400° F. and a thousand degrees F., iron, for example, has a specific heat of approximately 0.148. Therefore, $(1400-1000) \times 0.148 = 59$ B. t. u. are freed for absorption by the coal, 30 when one pound of iron drops from 1400° F. to a thousand degrees F. Inasmuch as 400 B. t. u. are required for one pound of coal, 400 divided by 59 equals 6.77 pounds of iron which are required to furnish sufficient heat 35 for elevating one pound of coal to a final temperature of approximately 1,000° F. In order to compensate for the slowing down of the heat transfer, as above explained, it is preferable to employ approximately twice as 40 much iron as the theoretical minimum, which would be approximately 14 pounds of iron for each pound of coal to be distilled.

By preheating the coal or drying it before bringing the coal into contact with the hot 45 iron, the amount of heat required for the distillation process may be materially reduced. This would permit the process to be carried on with a smaller quantity of iron. Even when preheating of the coal is employed, it 50 is preferable to employ enough iron in order that the heat available for distillation be about twice the amount of the theoretical minimum.

Referring to the drawings: There is shown 55 at 1 a distilling chamber having surrounding walls 2 formed of any suitable refractory material. Within the chamber 1 are parallel vertical walls 3 suspended from horizontal water-cooled suspension bars 4. These walls 60 may be each constructed of iron sections united by vertical rods 5 into the wall units, as shown. The heating gases for bringing the walls up to the required temperature enter the distilling chamber 1 through the mixing chambers 6 disposed on the opposite sides of

the distilling chamber, as shown in Fig. 4. Fuel gas may be supplied to the mixing chamber 6 through the pipes 7 and air through the pipes 8. The products of combustion discharge from the upper end of the distilling chamber 1 and above the vertical walls 3 through the outlets 9. 70

As shown in Fig. 2 the spaced vertical walls 3 taper slightly towards the top and provide between them long, narrow vertical retorts 10 into which the material to be distilled is charged from the upper end of the chamber 1. The retorts widen somewhat at their bottoms to facilitate discharge of the material. A pair of swinging doors 11 mounted on horizontal axes 12 below the heating walls 3 and the intermediate retorts 10 retain the material in contact with said walls 3 during the distilling operation. 75

After the walls have been heated to the required temperature, the supply of hot gases to the mixing chamber 6 is cut off and the discharge outlets 9 leading to the stack are closed by operating the dampers 13. During the operation of heating up the walls 3 the doors 11 are swung to the open position indicated by dot and dash lines in Fig. 2. On completion of the heating up operation the doors 11 are moved to the position for closing the bottoms of the retorts 10. Mounted above the distilling chamber is a truck 14 provided at one end with the pusher device 15, at the other end with a coal larry 16 and intermediate its ends with the retort cover and its operating mechanism 17. The retort cover is constituted of a horizontal plate 18 adapted to close the top of the distilling chamber 1. Said cover 18 is suspended from rods 19 the upper ends of which are pivoted to the lower arms 20 of bell-cranks pivoted at 21 on standards 22 mounted on the truck 14. The upper vertical arms 23 of said bell-cranks are provided with screw-threaded bearings 24 pivoted at 25 to the upper ends of said vertical arms. Working within the screw-threaded bearings 24 is a hand screw 26, which when operated in one direction will draw the vertical arms 23 together to lift the cover plate 18 from the distilling chamber 1, and, when operated in the opposite direction, will cause the vertical 115 arms 23 to retract from each other to lower the cover 18 into position on the top of the distilling chamber 1. 100

After the walls 3 have been heated up to the required temperature, the cover 18 is lifted from the top of the distilling chamber 1 and the truck 14 is moved to position the larry 16 above the distilling chamber. The larry 16 is provided with a plurality of coal hoppers 27 corresponding in number with the retorts 10 between the heating walls 3 and provided with dump bottoms 28 for feeding the coal into the said retorts 10. It is preferable to pulverize the coal before permitting it to discharge into the retorts. When the retorts 130

have been filled with coal, the truck 14 is again shifted to position the cover 18 above the distilling chamber 1 and said cover is lowered into position for closing the distilling chamber. The distillate outlet 29 is opened by operating the valve 29'. After the coal has been subjected for a sufficient period to the heat transfer action of the hot walls 3, the distillate outlet 29 is shut off by closing the damper 29, the cover 18 is again lifted from the top of the distilling chamber 1 and the truck is moved to position the pusher device 15 over the top of the distilling chamber. The pusher device is constituted of a movable frame 34 having opposite worms 30 in mesh with worm gears 31 journaled in bearings supported by a fixed form 32 mounted on the truck 14. Depending from the movable frame and supported thereby are pusher rods 33 corresponding in number with the retorts 10. During the operation of discharging the distilled material from the retorts 10 the doors 11 are thrown to the open position. The pusher rods are then lowered into the retorts 10 by operating the worm gears 31 and the downward movement of said pusher rods pushes out the distilled material into a hopper 35 located below the distilling chamber and from which the distilled material may be recovered as desired. After the distilled material has been pushed out of the retorts 10, the cover 18 may be reapplied to the distilling chamber and the walls 3 again heated up for a further distilling operation.

By the invention, the distillation of carbonaceous material is carried on at a very rapid rate. The heat is applied to the same surfaces, from which it is subsequently transferred to the coal. The heating walls are of very cheap material and large numbers of them may be employed. When distilling coal, the coke produced in accordance with the present invention separates readily from the surfaces of the heating walls, the troubles arising from sticking of the coke in low temperature distillations heretofore practiced being practically eliminated.

The invention as hereinbefore set forth may be variously embodied within the scope of the claims hereinafter made.

What is claimed is:

1. Apparatus for distilling solid carbonizable materials embodying: a distilling chamber; a plurality of long narrow vertical substantially flat and approximately parallel heat-storing plates within said chamber, said plates extending across said chamber from side to side and being spaced to provide a series of narrow retort chambers for the material to be distilled; a unitary means unitary with said distilling chamber and adapted to communicate with said distilling chamber for supplying gaseous heating media in the spaces among, and in contact with, the said heat-storing plates within said distilling

chamber; and separate offtakes communicating with the distilling chamber for the spent heating gases and the vapors of distillation respectively; substantially as specified.

2. The method of carbonizing solid carbonizable material in a carbonizing apparatus including a plurality of substantially parallel spaced vertical heat-storing plates which comprises: concurrently storing heat, effective for the carbonization, in said plates, discontinuing the storing of heat in said plates, then feeding the material to be carbonized into the spaces among said heat storing plates and carbonizing said material by transferring the heat previously stored in said heat storing plates directly to said material; substantially as specified.

3. The method of carbonizing solid carbonizable material in a single heating chamber which comprises admitting heating gases into said chamber and storing heat in a heat transfer medium positioned within said chamber; then cutting off the supply of said heating gases; and thereafter feeding the material into contact with the heat transfer medium in said chamber and carbonizing said material; substantially as specified.

4. Apparatus for treating solid carbonizable material embodying a distilling chamber; approximately parallel spaced heat-storing plates within said chamber; means for supplying gaseous heating media in the spaces among, and in contact with, said heat-storing plates and adapted for preheating said plates while within said distilling chamber and prior to introducing the carbonizable material therebetween; and means for removing gases of distillation from said chamber; substantially as specified.

5. The combination as defined in claim 4 in which the plates are approximately vertical and diverge slightly toward their lower ends.

6. The combination as defined in claim 4, in which horizontal suspension bars provided with means for water cooling thereof are employed from which the plates are suspended.

7. The combination as defined in claim 4, in which the plate are constructed of metal.

8. The combination as defined in claim 4, in which the plates are constructed of iron.

9. The improvement in the art of distilling solid carbonizable material which comprises, producing a carbonized residue of said material in cake form by effecting the entire volatilization by subjecting the material to contact with, and heat stored in, a solid heat-storing member heated out of contact with the carbonizable material undergoing carbonization to a temperature great enough to effect, by the heat stored therein during the heating period, the carbonization of the material by transfer thereto of part of its stored heat, and maintaining the material quiescent

with respect to the heat storing member throughout the major part of the carbonization; substantially as specified.

10. The improvement in the art of distilling solid carbonizable material which comprises, producing a carbonized residue of said material in cake form by effecting the entire volatilization by subjecting the material to contact with, and heat stored in, a metallic solid heat-storing member heated out of contact with the carbonizable material undergoing carbonization to a temperature great enough to effect by the heat stored therein during the heating period, the carbonization of the material by transfer thereto of part of its stored heat, and maintaining the material quiescent with respect to the heat-storing member throughout the major part of the carbonization; substantially as specified.

20. The improvement in the art of distilling solid carbonizable material which comprises, producing a carbonized residue of said material in cake form by effecting the entire volatilization by subjecting the material to contact with, and heat stored in, an iron solid heat-storing member heated out of contact with the carbonizable material undergoing carbonization to a temperature great enough to effect, by the heat stored therein during the heating period, the carbonization of the material by transfer thereto of part of its stored heat, and maintaining the material quiescent with respect to the heat-storing member throughout the major part of the carbonization; substantially as specified.

30. The improvement in the art of low temperature coking of coal which comprises, producing a coked residue of said coal in cake form by effecting the entire carbonization by subjecting the coal to contact with, and heat stored in, a solid heat-storing member heated out of contact with the coal undergoing carbonization to a temperature great enough to effect, by the heat stored therein during the heating period, the carbonization of the coal by transfer thereto of part of its stored heat, and maintaining the material quiescent with respect to the heat-storing member throughout the major part of the carbonization; substantially as specified.

40. The improvement in the art of low temperature coking of coal which comprises, producing a coked residue of said coal in cake form by effecting the entire carbonization by subjecting the coal to contact with, and heat stored in, a metallic solid heat-storing member heated out of contact with the coal undergoing carbonization to a temperature great enough to effect, by the heat stored therein during the heating period, the carbonization of the coal by transfer thereto of part of its stored heat, and maintaining the material quiescent with respect to the heat-storing

member throughout the major part of the carbonization; substantially as specified.

14. The improvement in the art of low temperature coking of coal which comprises, producing a coked residue of said coal in cake form by effecting the entire carbonization by subjecting the coal to contact with, and heat stored in, an iron solid heat-storing member heated out of contact with the coal undergoing carbonization to a temperature great enough to effect, by the heat stored therein during the heating period, the carbonization of the coal by transfer thereto of part of its stored heat, and maintaining the material quiescent with respect to the heat-storing member throughout the major part of the carbonization; substantially as specified.

15. The improvement in the art of carbonizing solid carbonizable material in a series of solid heat-storing plates spaced from each other so as to receive solid carbonizable material among them, which comprises, storing heat effective for the carbonization in said plates by heating the series of plates out of contact with the material to be carbonized, discontinuing said heating of said plates, then charging the carbonizable material among and in contact with said solid heat-storing plates, and carbonizing said material while among and in contact with said plates substantially entirely by the heat stored in the solid heat-storing plates in contact with said material.

16. The improvement in the art of carbonizing solid carbonizable material in a series of solid heat-storing plates spaced from each other so as to receive solid carbonizable material among them, which comprises, storing heat effective for the carbonization in said plates by heating the series of plates out of contact with the material to be carbonized, discontinuing said heating of said plates, then charging the carbonizable material among and in contact with said solid heat-storing plates, maintaining the solid carbonizable material in contact therewith until carbonized by the heat stored in said plates, discharging the carbonized material, and then reheating said series of solid heat-storing plates for effecting carbonization of further material.

17. The improvement in the art of low temperature coking of coal in a series of solid heat-storing plates spaced from each other so as to receive coal among them, which comprises, storing heat effective for the coking in said plates by heating the series of plates out of contact with the coal to be coked, discontinuing said heating of said plates, then charging the coal among and in contact with said solid heat-storing plates, and coking said coal while among and in contact with said plates substantially entirely by the heat stored in the solid heat-storing plates in contact with said coal.

18. The improvement in the art of low temperature coking of coal in a series of solid heat-storing plates spaced from each other so as to receive coal, which comprises, storing 5 heat effective for the coking in said plates by heating the series of plates out of contact with the coal to be coked, discontinuing said heating of said plates, then charging the coal among and in contact with said solid heat-storing plates, maintaining the coal in contact therewith until carbonized by the heat stored in said plates, discharging the coked residue, and then reheating said series of 10 solid heat-storing plates for effecting coking of further coal.

19. The improvement in the art of carbonizing solid carbonizable material in cake form in a series of parallel solid heat-storing plates spaced from each other so as to receive 20 solid carbonizable material among them which comprises: storing heat effective for the carbonization in said plates by heating the series of plates out of contact with the material to be carbonized by passage of heating gas among and in contact with said plates; discontinuing said heating of said plates; then charging the carbonizable material among and in contact with said plates; carbonizing said material by maintaining it in contact with said plates until carbonized by the heat stored therein during the heating period; and maintaining the material quiescent with respect to the heat-storing plates throughout the major part of 25 the carbonization.

20. The improvement in the art of low temperature coking of coal in cake form in a series of parallel solid heat-storing plates spaced from each other so as to receive coal among 30 them which comprises: storing heat effective 35

for the coking in said plates by heating the series of plates out of contact with the coal to be coked by passage of heating gas among and in contact with said plates; discontinuing said heating of said plates; then charging the 45 coal among and in contact with said plates; coking said coal by maintaining it in contact with said plates until coked by the heat stored therein during the heating period; and maintaining the coal quiescent with respect to the 50 heat-storing plates throughout the major part of the coking.

21. Apparatus for low temperature coking of solid carbonizable fuel comprising, in combination: a series of heat-storing walls arranged side by side and spaced a substantial distance from each other so as to provide between them retorting spaces for coking said solid fuel and respectively of heat-storing capacity adequate to effect low temperature 55 coking of a quantity of solid carbonizable fuel sufficient to fill the space between it and another of said walls adjacent thereto mainly by heat stored therein while retaining said walls in a solid state; means for heating said walls to store therein the heat for said coking, said means being adapted to effect said heating prior to introduction of said solid fuel in the spaces among said walls; means for introducing solid fuel into the retorting 60 spaces among said walls subsequent to the heating thereof; means for off-flow of gases of distillation from the retorting spaces among said walls; and means for discharging coked residue from said retorting spaces 65 among said walls; substantially as specified.

In testimony whereof I have hereunto set my hand.

FRANZ PUENING.
